UNITED STATES PATENT OFFICE

167,391

NECKTIE HOLDER

Arthur C. Braun, Maplewood, N. J.

Application March 26, 1951, Serial No. 14,630

Term of patent 3½ years

(Cl. D17—10)

To all whom it may concern:

Be it known that I, Arthur C. Braun, a citizen of the United States of America and a resident of Maplewood, in the county of Essex and State of New Jersey, have invented a new, original, and ornamental Design for a Necktie Holder, of which the following is a specification, reference being had to the accompanying drawing, forming a part thereof.

Figure 1 is a front elevational view of a necktie holder embodying my new design, the rear elevation being the same;

Figure 2 is a top plan view of the necktie holder; and

Figures 3 and 4 are end elevational views thereof taken from the respective planes 3—3 and 4—4 of Figure 1.

The characteristic feature of my design resides in the combination on the necktie holder disclosed of the contrasting stones in symmetrical settings on each side of the holder in association with the flanking rectangular elements, all as shown.

I claim:

The ornamental design for a necktie holder, as shown and described.

ARTHUR C. BRAUN.
